UNITED STATES PATENT OFFICE.

RICHARD F. ROBINSON, OF RIDGEFIELD PARK, NEW JERSEY.

COMBINED PAPER-WEIGHT AND CALENDAR.

SPECIFICATION forming part of Letters Patent No. 548,461, dated October 22, 1895.

Application filed February 7, 1895. Serial No. 537,647. (No model.)

To all whom it may concern:

Be it known that I, RICHARD F. ROBINSON, a citizen of the United States, residing at Ridgefield Park, in the county of Bergen and 5 State of New Jersey, have invented certain new and useful Improvements in a Combined Paper-Weight and Calendar, of which the following is a specification.

My invention relates to a combined paper- 10 weight and calendar, and has particular relation to that class of such devices in which a paper-weight is formed of glass or other like material and in which a calendar is located in such a manner as can be readily 15 seen when in use.

My invention consists in the improved construction and combination of parts, as will be hereinafter more fully described, and pointed out in the claim.

20 In the accompanying drawings, Figure 1 is a top plan view of my combined paper-weight and calendar. Fig. 2 is a vertical cross-section of the same. Fig. 3 is a bottom plan view, and Fig. 4 is an enlarged sectional view, 25 of the rotatable disks.

Similar letters of reference indicate similar parts in all of the figures of the drawings.

Referring to the drawings, A designates a 30 paper-weight, formed of glass or other suitable material, and which may be of any suitable shape, but is preferably of the form shown in Fig. 2. A circular recess a is formed in the base of the weight for the reception of the calendar.

35 B designates a calendar, of circular form, adapted to be secured in said recess, said calendar comprising a stationary disk b⁵, rotatable disks b⁴ and b³, stationary disk b², and securing cloth disk b. Eyelets b⁶ secure 40 disks b³ and b⁴ to the stationary disk b², for the purpose of forming a securing and pivoting point for each of said disks.

Disk b⁵ is adapted to contain the calendar- 45 numerals, arranged in concentric lines to correspond with the days of the week, as ordinarily arranged in monthly calendars. At the outer periphery of said disk an opening b⁷ is formed in juxtaposition to the concentric lines of numerals, and at a point inside of 50 and concentric with the calendar-numerals is located a rectangular opening b⁸, the object

of which will be hereinafter described. This disk forms the upper face of the calendar.

Rotatable disk b⁴ contains the names of the months or their symbols, arranged in a concentric line near its outer periphery in such position that the name or symbol of any month will be located below the opening b⁸.

Rotatable disk b³ contains the names of the days of the week or their symbols, arranged in such position that the days of the week will be seen below the opening b⁷. It is, of course, necessary that there should be a plurality of names or symbols in order to accommodate the disk and names or symbols to the varying of the days on which the same date falls in succeeding months.

The disk b² and the cloth disk b are preferably secured together in order to stiffen the calendar, and each of said disks have arranged 70 concentric with the eyelets b⁶ a plurality of openings, as clearly shown in Fig. 3, through which extend tabs, preferably formed of tape, ribbon, &c., and secured to the under side of the respective disks.

75 The operation will be readily understood by referring to the drawings, and it is not thought necessary to explain it in detail, except that the disks are changed at the end of each month by actuating the tabs and the 80 disks placed in proper position for the succeeding month.

The advantages of my invention are obvious, but among them may be mentioned its simplicity of operation, its durability, and its 85 cheapness, the whole forming a very neat, attractive, and useful desk ornament.

Having thus described my invention, what I claim as new is—

The combined paper weight and calendar 90 consisting of the transparent body or weight having a circular recess in its under side, and the circular calendar arranged in said recess and comprising the eccentrically pivoted disks, one bearing the symbols or data relating 95 to the days of the week, and the other containing data pertaining to the months, the stationary, top disk bearing the calendar numerals arranged in concentric lines and having viewing openings, one in its outer edge 100 portion adjacent to said lines of numerals and the other inside of, and concentric with,

said numerals and above the data relating to the months, and the bottom disk, with its cloth-covering disk, having openings through which are passed actuating tabs, and eyelets secured to said bottom disk and forming the pivots or axes for said pivoted disks, substantially as set forth.

In testimony whereof I have hereunto affixed my signature in the presence of two subscribing witnesses.

RICHARD F. ROBINSON.
